UNITED STATES PATENT OFFICE.

CHARLES F. LANGFORD, OF BROOKLYN, NEW YORK.

IMPROVEMENT IN SEAMS OF BOOTS AND SHOES.

Specification forming part of Letters Patent No. 129,970, dated July 30, 1872; antedated July 29, 1872.

SPECIFICATION.

I, CHARLES F. LANGFORD, of Brooklyn, in the county of Kings and State of New York, have invented a new and useful Improvement for Protecting and Strengthening the Seams of Ladies' Boots, of which the following is a specification:

In the ordinary manufacture of ladies' boots the quarters of the upper are closed together in a seam at the back of the heel, extending from the top down to the sole; the thread by which this seam is closed is left more or less exposed, so that the constant chafing of the hoop-skirt on the heel soon wears it off, thereby causing the parts to become separated, which defaces the boot and necessitates frequent repairs. It is the object of my invention to obviate these defects; and it consists in interposing between the quarters of the upper a strip or welt of India rubber or other suitable material, having a corded or rounded edge, which extends outside of the seam a sufficient distance to protect it from being worn by the skirt.

Figure 1 is a side elevation of the boot. Fig. 2 is a fragmentary view, showing the cord in front elevation.

As represented in the drawing, A is the boot, made in the ordinary manner; B, the strip or welt of India rubber, which is formed in a mold, with a corded or rounded edge. When the boot is to be made up the welt B is inserted between the quarters of the upper, so as to leave the corded or rounded edge projecting upon the outside, when the quarters are closed up by sewing, thereby forming a protection for the seam, and preventing the thread from being worn off, and at the same time giving strength to the seam, thus avoiding the necessity of frequent repairs.

I claim as my invention—

The rubber welt or guard B, having a corded or rounded edge, and arranged in relation to the seam substantially as described, and for the purpose set forth.

In witness whereof I have hereunto signed my name in the presence of two subscribing witnesses.

CHARLES F. LANGFORD.
